UNITED STATES PATENT OFFICE.

FRANK L. WANKE, OF CLEVELAND, OHIO, ASSIGNOR TO THE D. K. STEEL RANGE COMPANY, OF SAME PLACE.

KNOCKDOWN STOVE OR RANGE.

SPECIFICATION forming part of Letters Patent No. 540,932, dated June 11, 1895.

Application filed February 19, 1895. Serial No. 538,913. (No model.)

To all whom it may concern:

Be it known that I, FRANK L. WANKE, a citizen of the United States, residing at Cleveland, in the county of Cuyahoga and State 5 of Ohio, have invented certain new and useful Improvements in Knockdown Stoves or Ranges; and I do hereby declare that the following is a full, clear, and exact description of the invention, which will enable others 10 skilled in the art to which it appertains to make and use the same.

My invention has reference to knock-down cooking stoves or ranges, and the object of the invention is to construct a cooking stove 15 or range which can be taken apart and packed for shipment, and conveniently assembled and set up for use when it reaches its destination.

One of the chief difficulties in shipping 20 stoves to a remote market is the fact that they occupy very large individual space in the freight or express car and have to pay freightage or express according to their bulk rather than according to their weight. This is true 25 of all stoves and especially true of cooking stoves or ranges, which are very bulky in their proportions and hence expensive in transportation, especially for long distances, such as are found between the Eastern manufacturing 30 cities of our country and the outlying Western States and Territories. Indeed, so expensive has shipment been found that Eastern manufacturers have been unable to compete with manufacturers located in the West, and 35 all because of the large space occupied by a single stove or range. To overcome this objection I have sought to provide a range or stove which can be taken apart and packed so as to occupy practically no greater space 40 than the parts themselves must occupy by reason of their own size and shape. This result is obtained by producing a stove in separable parts, or what is properly known as a knock-down stove, adapted to be taken down 45 and set up by any one who is skilled in stove manufacture and who has some familiarity with the construction of the stove as herein shown and described.

The invention, therefore, consists in a 50 knock-down stove or range substantially as shown in the accompanying drawings and pointed out particularly in the claims.

In the accompanying drawings, Figure 1 is a perspective view of my improved stove or range. Fig. 2 is a longitudinal sectional elevation on a line corresponding to 2-2, Fig. 5. Fig. 3 is a cross-section of the stove on a line corresponding to 3-3, Fig. 4. Fig. 4 is a horizontal section looking down on a line corresponding to 4-4, Fig. 3. Fig. 5 is a perspective view of the stove, looking in at an angle from the front and side and showing some of the parts in position, and particularly those parts relating to the oven. Fig. 6 is a front elevation, in perspective, of the back plate of 65 the stove shown in position in Fig. 5. Fig. 7 is a front elevation of the rear oven-plate. Fig. 8 is a perspective view of the bottom plate of the oven and showing one side thereof bent downward at right angles and forming a support 70 therefor, as well as a side wall of the ash-pit, as hereinafter fully described. Fig. 9 is a perspective view of the front plate of the stove, corresponding to the view in Fig. 6 of the rear plate and looking against the inside of said 75 plate, as in Fig. 6, and showing, also, one of the side plates. Fig. 10 is a rear view of the back plate which is shown in perspective in Fig. 6. Fig. 11 is a perspective view, looking from the outside, of what may be termed 80 the "smoke-box," which belongs on the rear of the back plate seen in Fig. 10. Fig. 12 is a perspective view of a part of one corner of a stove, showing the manner of connecting the parts by the corner-posts. Fig. 85 13 is a perspective view of the warming-oven separated from the stove and having its cover or top plate raised to show its construction and adaptation for seating on the said frame. Fig. 14 is a perspective front elevation of the 90 door of the warming-oven.

Referring now to Figs. 1, 2, 3 and 4, we see the several parts in their assembled relations, while in Figs. 5, 9 and 13, only some of the parts are assembled, and the remaining figures are details of parts. Each and all of the parts are constructed with reference, primarily, to their place and use in the stove, and, secondarily, with reference to their convenience for shipment in a compact form; 95 lastly, they are constructed to effect such temporary connection and union, one with another, as to make a firm and serviceable stove when erected and at the same time to 100

be convenient for separation and for packing. To these several ends I have found it altogether preferable to make the stove of steel plate, so that when it is erected it produces what is known as a steel stove or range.

Assuming, now, that the construction has been knocked down and shipped and reached its destination where it is again to be set up, we begin to assemble and build the parts together as they are seen partly assembled in Fig. 5. First of all, let us assume that we take the back plate A, which has its vertical edges 2 and 2 bent outwardly at right angles, and a flange 4 along its top edge with a recess 5 at the middle thereof for the smoke box or flue. Then we have the side plates B which are provided each with vertical right angled flanges 5, respectively, at their front and rear, and the front plate C, which has right angled vertical flanges 6 at its edges and horizontal flange 7 along its top. All of these several plates have an angle strip 8 on their inside a short distance from their bottom edge and riveted on said plates and on the same horizontal plane and adapted to receive the downwardly projecting flange or edge 9 on the stove bottom proper, or bottom plate D of the stove. This flange 9 extends entirely around the edge of plate D, and engages over the angle strips 8. In assembling the parts, it is convenient to connect the side and the front and rear and bottom plates together before putting into position and of the internal parts except the division plate or wall E on the bottom D. This division plate is made T-shaped and engages beneath the angle strips 12 on the bottom plate D to form a division wall in the flue or draft channel at the bottom of the stove as clearly seen in Fig. 5.

When the four several wall plates A, B and C, which form the shell of the stove are assembled, their angled vertical edges or flanges stand at right angles to each other, or substantially so, as clearly seen in Fig. 12. Then, in order to connect the meeting wall plates at their angles and make a firm and ornamental corner connection, I employ the preferably cast metal corner posts F. These posts are substantially cylindrical in cross section, as here shown, but they may have other form in exterior outline if preferred, and may be of more or less ornamental appearance than as shown, and have each four faces in pairs at right angles to each other and extending lengthwise of the posts and corresponding to the angle of the edges and faces of the said plates. Thus, referring to Fig. 12, and assuming that we have there a corner of plates B and C, and it is immaterial which corner is taken for the purpose of this description, we find that the two inner meeting faces b and c, respectively, make a flush corner of said plates, and that their flanges, 5 and 6, project outward from b and c, respectively, at right angles to b and c and also to each other. The corner post F therefore, is constructed to face against both sides of the angle between b and 5 on the out-

side of the plate B, and the same with respect to the angles between c and 6 in the plate C, and it has vertical faces to correspond to the outside of both said angles their full depth and to fill the same and is so constructed that when it has been slid down over the corner of the said plates thus formed, the said plates will be brought together at their corners at right angles to each other and will be immovably and firmly tied together for all the purposes of use, the same as if they were originally formed in a single piece or were rigidly and permanently bolted together. Each of the four corners is provided with the same style of post as shown in Fig. 12, and the several four said side plates and the bottom plate are tied together with each other and with the said posts as described, and this may be considered the first step in assembling the parts of the stove.

Now, having the box of the stove set up in this way, we may proceed to place other parts in position. Next in order, then say we take the bottom oven plate G, Fig. 8, which has a downwardly projecting flange 10 along its front and rear edges, respectively, adapted to engage over an angle piece 12' on the inside of the front plate and a corresponding angle piece 13 on the inside of the back plate. This plate G, however, is shown also as having at one end a downwardly extending portion 15, which in turn has a right angle flange 16 at its bottom adapted to engage under an angle piece 17 on the stove bottom D. The portion 15 of the plate G constitutes a wall between the flue under the oven plate and the ash pit, and the said portion is preferably shown as formed out of the same plate as the bottom portion G. I might, of course, form 15 separately from G and connect them in some suitable way. This plate G has a series of grooves or depressions 18 stamped into it which run from front to rear thereof and are intended to accommodate expansion and contraction resulting from the ordinary actions of the stove under heat or cold. Said plate, furthermore, has grooves or channels 20 formed along its sides and adapted to set therein the two side plates H— and —I— respectively. These plates at their rear have right angled flanges 22 and 23 adapted to engage behind the vertical angle pieces 24 riveted to the back plate A of the stove. These angle pieces 24 are made deep enough in their angles to also accommodate the flanges 25 on the vertical edges of the warming plate K, which is set in next to the rear plate A behind said angle pieces 24 and has a flange 26 along its bottom engaging behind the angle piece 13, Fig. 6. This plate K is constructed to form a heat circulating chamber at the rear of the oven, as plainly seen in cross section, Fig. 4, and has a series of perforations 27 at its top and bottom respectively so as to promote a draft in the chamber behind it and to facilitate heating the oven at that part where otherwise the tendency would be to cool. Over

the top of the oven thus formed we have a top plate L which has down flanges 30 along its edges engaging in corresponding grooves in the side plates H and I, which grooves are formed by bending the said side plates in such ways as to form substantially U-shaped grooves of a size adapted to receive and lock the flanges 30 of the plate L. This top plate L likewise has a series of parallel depressions 33 adapted to compensate expansion and contraction of the plate. The back plate has two draft outlets 34 and 35 respectively, the outlet 34 at the top being for direct draft, and the outlet 35 at the bottom being for indirect draft around the oven and following the direction of the arrows in Fig. 5. The smoke box M shown in Fig. 11 is adapted to be attached to the outside of the back plate A within the angle strips 36, Fig. 10, and has flanges 37 along its edges to engage in said angle strips. This box is inserted from above and of course is easily removed and replaced.

Referring to Fig. 5 it will be seen that plates B and H, respectively, between which comes the fire pot, are provided with angle pieces 40 and 41, which extend inward toward each other and form supports for the fire grate as seen in Fig. 2, and the grate bars N are arranged on a line substantially with these angle strips.

Referring to Figs. 3 and 4, I show an air chamber in the oven door corresponding in purpose and function to a like chamber at the rear of the oven and formed of two plates, O and P, front and rear respectively, and connected along their side edges by the castings 44 to which they are riveted, and together with said castings form a front oven door. The front plate O has a ventilator 45 in its center.

Overall the parts as hereinbefore described, I place a cast metal top plate R of the stove, which is secured by short screws to the flanges along the top edges of the plates forming the box of the stove and thus the main structure of the stove is made complete.

Now, as a finishing part I have the warming oven, set on the stove as described. This oven consists of end plates 48 having flanges 49 along their bottom through which they are secured to the top plate of the stove, and the back plate 50 having a flange 51 at its bottom for securing it to the top plate of the stove. These three several plates 48 and 50 have corner posts 52 for connecting them at their flanged or right angled corners after the manner of connecting the four sides of the stove proper, and the said several plates have angle bars 53 on their inside to receive the intermediate bottom 54, which is set upon said angle plates. Around about the top edge of the said side and back plates 48 and 50 are angle strips 55 which come flush with the top of the said plates, and the cover 56 has its edges bent down at right angles as seen at 57

to engage in said angle plates 55 and thus the warming oven is completed. It will be noticed that the side plates 48 have an inwardly bent portion 60 at their top and front engaging against the front edge of the plate 54 and forming a finish along this edge, and the door S Fig. 14 has ears 62 at its ends by which it is hinged at 63 in the side plates 48, Figs. 13 and 5, and is adapted to be raised and lowered within the warming oven. The pipe or flue T extends through this warming oven as seen in Fig. 3, and a suitable damper 66 controls the direct draft opening 34.

What I claim is—

1. In a knock down stove, the four several removable outside plates of the stove, united at their corners and the bottom plate removably secured thereto, in combination with bottom oven plate —G— formed with channels —20— and having down portion —15— and securing strip —17— therefor on bottom —D—, the support —E— beneath the plate —G—, the side plates —H— and —I— having channels —30— at their top and the top plate —L— having down flanges resting in said channels —30—, substantially as set forth.

2. In a knock down stove, the respective side, front and rear plates having strips —8— along their inside faces and the bottom plate —D— seated therein along its edge, said rear plate having horizontal angle strip —13— and combined with and supported from the bottom of the stove by down portion —15— and plate —E—, strips —24— with which the side plates —H— and —I— engage, and the top plate —L— engaging said side plates at their top edges, substantially as set forth.

3. The knock down stove described, having back plate —A— with angle strip —13— and angle strips —24— on its inside, and the plate —G— fixed in said strip —13— the side plates —H— and —I— engaged in said strips —24— and the perforated chamber plate —K— at the rear of the oven and having flanges engaged in said strips —13— and —24— behind the plates —G— —H— and —I—, and the top plate —L— covering the oven and back chamber, substantially as set forth.

4. The warming oven described, comprising the end plates —48— and the back plate —50— detachably united at their corners, the said end and back plates having channel strips —53— and —55—, respectively, at different elevations, the shelf —54— and the cover —56— having flanges at their edges engaging in said strips and the door —S— at the front of the oven, substantially as set forth.

Witness my hand to the foregoing specification this 4th day of February, 1895.

FRANK L. WANKE.
